VACUUM CLEANER

John Frederick, New York, N. Y.

Original application November 4, 1937, Serial No. 172,667. Divided and this application December 12, 1939, Serial No. 308,765

2 Claims. (CL 15—4)

This invention relates to vacuum cleaners in which an impeller of known type provides the suction means.

The present application is a division of my application Serial No. 172,667 filed November 4, 1937.

An object of the invention is the provision of a suction inlet in addition to the usual inlet, so located that the suction means of the cleaner may readily be availed of for removing dust, lint or similar material from a mop, brush or like cleaning implement.

A feature of the invention resides in the provision of a suction inlet in addition to the usual suction inlet, situated directly above the latter and so proportioned and arranged as not materially to interfere with the use of the vacuum cleaner when it is desired to clean under furniture which is close to the floor. More particularly the vacuum cleaner is provided with a casing having a lower front portion and a higher rear portion, a suction inlet being formed in the bottom of the low front portion with an upwardly facing inlet formed in the top of said portion which latter inlet is covered by a mop cleaning grid.

Various advantageous features of the invention will become apparent from the following description and claims when taken in connection with the accompanying drawing in which:

Figure 1 is a perspective view of a vacuum cleaner of known type with my improvement applied thereto; said view also showing one type of cleaning implement which my improved device is adapted to clean;

Figure 2 is a side elevation partly in section of the type of vacuum cleaner shown in Figure 1;

Figure 3 is a section on the line 3—3 of Figure 2;

Figure 4 is a top plan view;

Figure 5 is a view taken on the line 5—5 of Figure 2; and

Figure 6 is a section on the line 6—6 of Figure 5.

Referring to Figure 2, the vacuum cleaner there depicted includes the usual casing 1 which houses the motor and on a shaft 2 supported in said casing, Figure 3, is the usual impeller 3 constituting the suction means. The usual rollers 4 are also provided whereby the cleaner may be moved about. The usual suction inlet 5 faces downwardly for cleaning the surface over which the cleaner is moved and when the impeller is put in motion, air passes into the suction inlet 5 through the conduit 6 thence to the impeller chamber

from which it passes through the connection 8 to the dust receiving bag 10, Figure 1. A removable member 5' is provided to facilitate other attachments.

The parts above described are those usually found in a vacuum cleaner of the type illustrated.

In carrying out my invention, I provide a second suction inlet which preferably is situated immediately above the inlet 5 and faces upwardly and consists of a very shallow supplemental casing 12 into which a grid 13 is formed. The grid may be made as a separate piece and fitted into the casing 12. Air may pass through the openings in the grid to the conduit 14 and thence to the impeller or it may pass through the intake 5 depending upon the position of a valve 15 so positioned that it may close either the conduit 14 or the conduit 6. A partition 15a separates the two conduits. In the position shown in Figure 2, the conduit 6 is closed and hence suction takes place only through the grid 13. The valve is supported on a shaft 16, Figures 5 and 6, which shaft is provided with a small lever 17 by which it may be moved from the full line position shown in Figure 6 to the dotted line position there depicted. The valve is maintained in either position by a spring pressed plunger 18 engaging one or another of two notches provided in a disc 19.

The openings in the grid are preferably largest near the center and gradually diminish in area and width as they approach each end of the grid. The material separating the openings constitutes a means whereby material adhering too tightly to the implement to be cleaned, for effectual removal through the suction, may be loosened by moving the implement back and forth over the grid.

The area of the grid openings as compared to the area of the suction inlet 5 is so proportioned that the desired suction is maintained at the grid inlet.

By reason of the particular construction of the casing having a low front portion with one suction inlet immediately below and the other suction inlet immediately above enables the vacuum cleaner to be moved under objects which lie close to the floor, at the same time providing a convenient means whereby the mop may be cleaned by placing it upon the grid which overlies the upper suction inlet.

50 What I claim is:

1. In a vacuum cleaner, a casing having a shallow projecting front portion of substantially uniform thickness, a downwardly facing suction inlet formed in the bottom of said front portion and at the forward end thereof, said shallow

front portion adapted to be applied directly to and moved over the surface to be cleaned, the height of said front portion being such as to permit it to be passed under relatively low furniture, an upwardly facing suction inlet formed in the top of said shallow front portion and within the confines of said front portion, and a mop cleaning grid covering said upwardly facing suction inlet.

2. In a vacuum cleaner, a casing having a shallow projecting front portion of substantially uniform thickness, and a higher rear portion, a downwardly facing suction inlet formed in the bottom of said shallow front portion and at the forward end thereof, said shallow front portion

5 being adapted to be applied directly to and moved about over the surface to be cleaned, the height of said shallow front portion being such as to permit it to be passed under relatively low furniture, an upwardly facing suction inlet formed in the top of said shallow front portion, a mop cleaning grid covering said upwardly facing suction inlet, a suction source formed in said higher rear portion of said casing, a conduit leading from said suction source, and a means for connecting at will one or the other of said suction inlets to said conduit.

10 JOHN FREDERICK.
